Primary Examiner — Catherine S Posthauer

(57) **CLAIM**

The ornamental design for a cup connector, substantially as shown and described.

DESCRIPTION

FIG. 1 is a top perspective view of a cup connector showing our new design;

FIG. 2 is another top perspective view thereof;

FIG. 3 is a bottom perspective view thereof;

FIG. 4 is a top view thereof;

FIG. 5 is a bottom view thereof;

FIG. 6 is right side view thereof;

FIG. 7 is a front view thereof;

FIG. 8 is left side view thereof;

FIG. 9 is a rear view thereof;

FIG. 10 is a right side view thereof shown in a position of use with an exemplary cup and lid;

FIG. 11 is a top perspective view thereof;

FIG. 12 is an exploded top perspective view thereof; and,

FIG. 13 is another exploded top perspective view thereof.

The broken lines for the example cup and lid in FIGS. 10-13 are for illustrative purpose only and form no part of the claimed design.

1 Claim, 13 Drawing Sheets
